United States Patent Office

Des. 189,428
Patented Dec. 13, 1960

189,428

DENTAL LIGHT

John A. Salvia, Rochester, N.Y., assignor to Wilmot
Castle Company, Rochester, N.Y., a corporation of
New York

Filed Dec. 1, 1958, Ser. No. 53,587

Term of patent 14 years

(Cl. D48—20)

FIG. I

Des 189,428

PAGE 2

FIG. 2

FIG. 3

FIG. 4

FIG. 5

Fig. 1 is a perspective view of a dental light showing the new design;

Fig. 2 is a front elevational view thereof;

Fig. 3 is a side elevational view thereof;

Fig. 4 is a top plan view thereof; and

Fig. 5 is an enlarged fragmentary horizontal sectional view taken on the line 5—5 of Fig. 1.

The dominant features of my design reside in the portions shown in full lines.

I claim:

The ornamental design for a dental light, substantially as shown and described.
